ATTACHMENT FOR MAKING PLUG BRICKS

John B. Blewett, Wellsville, Ohio, assignor to The McLain Fire Brick Company, Pittsburgh, Pa., a corporation of Delaware

Application July 22, 1943, Serial No. 495,724

8 Claims. (Cl. 25—44)

The present invention relates to mechanism for forming expanded holes in ingot mold plug bricks.

The primary object of the invention is to provide an apparatus to be used in conjunction with the refractory plug brick mold to produce a refractory plug brick having an opening in the center thereof which has an enlarged internal area and a reduced throat portion.

A further object of the invention is to provide an apparatus for producing a refractory plug brick adapted to be received in the bottom wall of an ingot mold, whereby the plug brick will become attached to the ingot during stripping, transportation and soaking and when it is necessary to have a refractory base or support for the ingot.

A still further object of the invention is to provide an apparatus which will automatically form an opening in the center of a plug brick, whereby said opening will have a reduced throat portion after the completed operation.

Other objects and advantages of the invention will become apparent during the course of the following description of the accompanying drawings wherein:

Figure 1 is a top elevational view of the revolving head which carries the opening forming mechanism.

Figure 2 is a side elevational view illustrating in detail the arrangement of the presser plate and former operating mechanism.

Figure 3 is a side elevational view taken at right angles to Figure 2 further illustrating in detail the operation of the presser head and forming member.

Figure 4 is a vertical cross sectional view taken on line 4—4 of Figure 3 looking in the direction of the arrows showing the manner in which the former is held in its retracted position.

Figure 5 is a vertical cross sectional view similar to Figure 4 illustrating the former in its extended position.

Figure 6 is a vertical cross sectional view taken at right angles to Figures 4 and 5, further illustrating the opening former in its extended position.

Figure 7 is a horizontal sectional view illustrating the manner in which the former is projected into the plug brick during the initial portion of its operation.

Figure 8 is a horizontal cross sectional view illustrating the manner in which the former is rotated when the plug brick is moved upwardly into engagement with the presser head.

Figure 9 is a detail side elevational view of one

of the pivot members employed for supporting the opening former.

Figure 10 is a vertical sectional view of the former illustrating a central bore therein through which a portion of the refractory clay is removed during the forming operation, and,

Figure 11 is a fragmentary sectional view of one of the completed plug bricks produced in accordance with this invention.

In the drawings, wherein for the purpose of illustrating the invention, and wherein like reference characters will be employed to designate like parts throughout the same, the reference character 10 will generally be employed to designate a rotating carrier having openings 12 therein for being bolted to a spinner head which is commonly used in connection with refractory plug brick molds, and which spinner head is adapted to be rotated but is not capable of axial movement. The spinner head is not shown for the reason that any suitable means may be employed for rotating the carrier 10.

The carrier 10 is substantially circular and is provided with opposed flattened surfaces 14. Separable sections 16 and 18 are provided to form the carrier and include complementary meeting faces 20 and 22 which are connected together by a transverse shaft 24.

A series of openings 26 are formed in circular spaced relation in the carrier 10 for receiving a series of bolts 28 having heads 30 which limit the downward movement of the bolts. A circular presser plate 31 is provided with similar openings for receiving the lower screw threaded ends of the bolts 28, as at 32 on which are threaded bolts 34 to thereby space the presser plate 31 from the carrier head 10. Coil springs 36 are mounted on the bolts 28 and maintain the presser plate 31 in spaced relation to the carrier 10.

Secured to the flattened portions 14 of the head 10 is a pair of angle brackets 38 which are held in place by bolts 40, which act as pivots and the angle portion 42 of each bracket is secured to an angle bracket 44 by means of bolts 46 having threaded on the ends thereof nuts as at 48.

Pivotedly attached to the angle brackets 44 is a pair of triangular pivot plates 50 by means of bolts 52 which extend through openings 54 and are held therein by means of set screws 56. The pivot pins 52 are unthreaded so that the triangular plates 50 may freely pivot on the brackets 44. The carrier 10 is cut away as at 51 to allow free movement of the pivot plates 50.

Depending from the presser plate 31 at diametrically opposite points are pivot blocks 58 hav-

ing pivot pins 60 which extend through openings 62 (see Fig. 9) in the triangular plates 50 so that the triangular plates 50 will rock thereon when the presser plate 31 is raised and lowered against the tension of the coil springs 36. Set screws 64 are carried by the depending pivot blocks 58 to retain the pivot pins 60 in place.

Each of the triangular plates 50 is provided with openings 66 in one corner thereof, having transverse or lateral threaded bores 68 for receiving set screws so that the ends of a connecting rod 70 may be anchored therein and held against lateral movement and against rotating movement.

Secured to the central portion of the connecting bar 70 is an arcuately curved forming plunger 72, the free end of which is beveled as at 74 to terminate in a blunt point 76. The arcuately curved former 72 is adapted to operate in an offset opening 78 formed in the presser plate 31 and said opening is of such formation as to allow the former 72 free movement therethrough when the presser plate 31 is raised and lowered.

The former mechanism above described is intended to be used in connection with a circular mold 80 which is raised and lowered automatically and is provided with a circular tapering opening 82' for receiving a batch of clay 82 to be molded. The mold 80 is also provided with a bottom wall 84 and the top wall is formed by the presser plate 31 when the mold 80 is automatically brought up into engagement therewith as shown in Figures 5 and 6.

When the mold 80 is moved upwardly by means of automatic mechanism which is believed unnecessary to show or describe, as such mechanisms are used in refractory plug brick molding machines, the rotating presser plate 31 rotates over the upper surface of the refractory clay 82 and smooths the same to prevent the formation of holes or other irregularities therein.

Limit blocks 86 are provided on the undersides of the carrier 10 to limit the upward movement of the presser plate 31, and the bottom wall of the carrier 10 is cut away as at 88 to allow the free passage of the triangular pivot plates 50 and their connecting bar 70.

In operation, the mold 80 is moved upwardly and contacts the presser plate 31 which is rotating at a rapid rate of speed with the carrier 10. Upon a continued upward travel of the presser plate 31, as by means of the mold 80, the triangular plates 50 are rocked on their pivot pins 52 by means of the pivot pin and pivot block 58 carried by the presser plate 31. As the triangular pivot plates 50 rock about the pivot 52, in an upward direction, the former 72 and connecting rod 70 are simultaneously rocked so that the former 72 will project through the opening 78 to allow the free blunt end 76 to enter the mass of refractory clay 82 and thereby remove the clay from an enlarged area 90. The point at which the former enters will be reduced or restricted as at 92 and a portion of the removed clay will pass upwardly through a central bore 94 in the arcuately curved former 72 which will have been collected through openings 96 in the pointed end thereof.

By adjusting the bolts 30, the carrier 31 may be raised or lowered to limit the projection of the arcuately curved former 72 to produce enlarged areas 90 of different sizes and formations.

The plug brick as shown completed in Figure 11 is formed of refractory clay and is inserted in the bottom wall of an ingot mold so that the

molten metal when poured in the mold, will enter the enlarged area 90 of the plug to cause the plug to be anchored to the ingot when the cast metal solidifies. When the ingot is removed from the mold, the plug brick is carried on the bottom thereof. It is to be understood that the form of the invention herewith shown and described is to be taken as a preferred embodiment of the same and that various changes in the shape, size and arrangement of parts may be resorted to without departing from the spirit of the invention or the scope of the subjoined claims. For example, by adjusting the bolts 30 to raise or lower the carrier 31 or adjusting the bolts 46 which connect brackets 42 and 44, and by using shims between said brackets, or changing the length or profile of the forming plunger 72, an increase or a decrease of the projection of the arcuately curved former 72 may be effected, and will result in the enlarged areas 90 being made of any different or desired size or formation.

What is claimed is:

1. For use with a plug brick mold, a carrier adapted to be attached to a spinner head, a presser plate resiliently mounted on the carrier, a pair of rocking plates pivoted to the carrier and presser plates and a former operably connected to the rocking plates and adapted to form a central opening in the material being molded.

2. For use with a plug brick mold, a carrier adapted to be attached to a spinner head, a presser plate resiliently mounted on the carrier and adapted to be engaged by the plug brick mold, links pivotally attached to the carrier and presser plate and a former operably connected to the links adapted to project through the presser plate to form an opening in the material being molded.

3. For use with a plug brick mold, a carrier adapted to be attached to a spinner head, a presser plate suspended from the carrier, an arcuately curved former adapted to project through the presser plate and means for projecting the former through the said presser plate upon the upward movement of the plug brick mold.

4. For use with a plug brick mold, a carrier adapted to be attached to a spinner head, a presser plate suspended from the carrier, an arcuately curved former supported by the carrier and presser plate and adapted to project through an opening in the presser plate, and means suspended by the presser plate for projecting the former through the presser plate when the plug brick mold is moved upwardly into engagement with the said presser plate.

5. For use with a plug brick mold, a carrier adapted to be attached to a spinner head, a presser plate resiliently suspended from the carrier, an arcuately curved former pivotally supported by the carrier and presser plate and adapted to be projected through an opening in the presser plate, and means operable upon the upward movement of the plug mold into engagement with the presser plate to move the former to penetrate the said presser plate and into its operative position.

6. For use with a plug brick mold, a carrier adapted to be attached to a spinner head, a presser plate resiliently suspended from the carrier, an arcuately curved former pivotally attached to the carrier and presser plate and adapted to project through an opening in the presser plate, and means operable upon the upward movement of the brick plug mold into engage-

ment with the presser plate to project the former through the said presser plate and into the said plug brick mold.

7. For use with a plug brick mold, a carrier adapted to be attached to a spinner head, a presser plate resiliently suspended from the carrier, an arcuately curved former adapted to be projected through the central portion of the presser plate, and means operable upon the upward movement of the plug brick mold and presser plate to project the arcuately curved former.

8. For use with a plug brick mold, a carrier

adapted to be attached to a spinner head, a presser plate suspended from the carrier, spring means for urging the presser plate downwardly, a pair of rocking triangular shaped plates pivotally attached to the carrier and presser plate, a bar connecting the rocking plates, an arcuately curved former made integral with the connecting bar and adapted to be projected through an opening in the presser plate, and means operable upon the upward movement of the plug brick mold to project the former into the mold centrally thereof.

JOHN B. BLEWETT.
